(57) **CLAIM**

The ornamental design of a shoe, as shown and described.

DESCRIPTION

FIG. 1 is a top perspective view of a shoe;

FIG. 2 is a bottom perspective view thereof;

FIG. 3 is a first side view thereof;

FIG. 4 is a second side view thereof; and,

FIG. 5 is a rear view thereof.

The broken lines in the figures depict portions of the shoe that form no part of the claimed design.

1 Claim, 5 Drawing Sheets
